(57) **CLAIM**

The ornamental design for a collapsible golf tee/ball stand, as shown and described.

DESCRIPTION

FIG. 1 is a front perspective view of a ball stand showing my new design in receipt of an exemplary golf ball;

FIG. 2 is a top plan view thereof;

FIG. 3 is a bottom plan view thereof;

FIG. 4 is a rear orthogonal elevation thereof;

FIG. 5 is a front orthogonal elevation thereof;

FIG. 6 is a side orthogonal elevation thereof; and,

FIG. 7 is a plan view thereof, in an unassembled condition.

The broken and dashed lines in FIGS. 1, 2, 5-7 are for illustrative purposes only and form no part of the claimed invention.
